Des. 222,504
Patented Oct. 26, 1971

222,504

ELECTRONIC THERMOMETER READ-OUT HOUSING

Stephens N. Sato, San Diego, Calif., assignor to Ivac
Corporation, San Diego, Calif.

Filed Aug. 6, 1970, Ser. No. 24,337

Term of patent 14 years

Int. Cl. D10—04

U.S. Cl. D52—7

FIG. 1 is a perspective view of an electronic thermometer read-out housing showing my new design;

FIG. 2 is a right side elevational view of the thermometer shown in FIG. 1;

FIG. 3 is a front elevational view of the thermometer shown in FIG. 1;

FIG. 4 is a rear elevational view of the thermometer shown in FIG. 1; and

FIG. 5 is a bottom plan view of the thermometer shown in FIG. 1.

I claim:

The ornamental design for an electronic thermometer read-out housing, as shown.
